Assistant Examiner — Ryan Harvey

(57) **CLAIM**

The ornamental design for a gaming terminal, as shown and described.

DESCRIPTION

FIG. 1 is a perspective view of a gaming terminal showing my new design;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a top plan view thereof;

FIG. 7 is a bottom plan view thereof; and,

FIG. 8 is a bottom perspective view thereof.

The broken line showing of fasteners and vents is included for the purpose of illustrating environmental structure and forms no part of the claimed design.

1 Claim, 8 Drawing Sheets
